DOUBLE SHAFT ARROW

Howard F. Ellenburg, Rte. 3, Columbus 31, Nebr.
Filed June 5, 1963, Ser. No. 285,624
2 Claims. (Cl. 273—106.5)

This application is a continuation-in-part of the pending application Serial No. 165,122, filed January 9, 1962, and titled "Double Shaft Arrow," now abandoned.

This invention relates to hunting and fishing arrows of the retrievable type, and more particularly it is an object of this invention to provide an arrow which will shoot straight because its retrieving line is attached to its rearward end during flight, the arrow being constructed in a new way so as to be safe to use.

Heretofore when lines have been attached to the rearward ends of arrows before the arrow is released, there has been a serious danger lest the line carried forward toward the bow handle at top speed catch around a finger of the archer tearing off the skin, or causing even more serious injury.

It is a particular object of this invention, therefore, to provide an arrow so constructed that the retrieving line is connected to the arrow at its forward end at a time before and during release of the arrow, the line-to-arrow connection sliding rearwardly along the arrow to a fixed position at the rearward end of the arrow only after the arrow is safely in full flight.

A further object is to provide an arrow as described which is accurate due to the provision on the arrow of at least one side of the arrow having its outer surfaces without a substantial protrusion whereby when that side of the arrow is disposed against the side of a bow during shooting, the arrow will not be substantially deflected off the course by any portion of the arrow which might otherwise protrude substantially beyond such one side surface and cause a deflection by striking the bow during arrow release.

Still another object is to provide an arrow particularly adapted for fishing, being adapted to move through the water more swiftly than arrows of the prior art, as is important because water resistance is vastly greater than air resistance.

A particular object is to achieve a high speed water arrow having a small total cross-sectional area for greater penetration. The achievement of a small cross-sectional area is made possible in combination with the safety feature above described due to a unique design embodying two parallel shafts serving as a trackway of minimum cross-sectional area, whereby a track follower is defined by a loop of a retrieving line extending about one of the shafts.

A still further object is to provide an economic retrieving arrow combination as described with both safety features and accuracy features.

A particular object is to provide an arrow partially achieving its high water penetration because of great strength per unit of cross-sectional size and partly through manufacture of the arrow from metal, preferably spring steel.

A particular object is to provide a bow string notch in an arrow of minimum cross section for encountering the least water resistance for greatest depth of penetration inasmuch as single shaft arrows of the prior art which are wide enough to accommodate an adequate bow string notch necessarily have larger diameter and greater cross section.

Other and further objects and advantages of the present invention will be apparent from the following detailed description, drawings and claims, the scope of the invention not being limited to the drawings themselves as the drawings are only for the purpose of illustrating a way

2

in which the principles of this invention or equivalent principles may be used and structural changes may be made as desired by those skilled in the art without departing from the present invention and the purview of the appended claims.

In the drawings:

FIGURE 1 is a side elevational view of a bow with an arrow of this invention in shooting position thereon, and with the arrow connected by a line to a reel on the bow.

FIGURE 2 is a view showing the point or head of the arrow shown in FIGURE 1, with the arrow shown on an enlarged scale and with the lower part of the arrow broken away; and this view also shows a retrieving line attached to the arrow at a point spaced from the head.

FIGURE 3 is a plan view of the arrow, with the intermediate portion thereof broken away, illustrating the connections of the spaced shafts, and also showing a line attached to the shafts, the parts also being shown on an enlarged scale.

FIGURE 4 is a side elevational view of the arrow, positioned as shown in FIGURE 1, and with the retrieving line extended from the trailing end.

FIGURE 5 is a plan view of the rearward end of a modification of the arrow of FIGURE 3.

FIGURE 6 is a side elevational view of the arrow of FIGURE 5 as seen from the right hand side.

FIGURE 7 is a plan view of the rearward end of a still further modification of the arrow of FIGURE 3.

FIGURE 8 is a side elevational view of the arrow of FIGURE 7 as seen from the right hand side thereof.

In the accompanying drawings, and in the following specification, the same reference characters are used to designate the same parts and elements throughout, and in which the numeral 10 refers to the invention in its entirety, numerals 12 and 14 indicating shafts of an arrow 16, numeral 18 indicating a point, numeral 20 indicating a retrieving line, numeral 22 a reel, and numeral 24 indicating a bow.

The shafts 12 and 14 are preferably formed of metal and still more preferably of stainless steel so that they have a high density and great strength per cross-sectional area so that the cross-sectional area of the arrow can be kept at a minimum for providing an arrow having other features herein described so that the minimum cross section will encounter a minimum of water resistance providing high penetration at great water depth.

The trailing ends of the shafts, which are inclined outwardly, are secured together and in spaced relation by a weld 26, and the opposite or leading ends which are secured to the point 18 by brazing at the points 28 and 30, are provided with inwardly inclined sections 32 and 34, and inner surfaces of the sections 32 and 34 are flat to receive the point 18.

The head or point 18 is provided with inclined edges 36 and 38 which extend from the tip 40 to points 42 and 44, and from the points 42 and 44 the trailing end of the point extends forwardly and inwardly on lines 46 and 48 to a point 50 between the shafts.

The line 20 is provided with a loop assembly or track follower 52 that receives both of the shafts and extends around at least one of the shafts, and in the retracted position the line is wrapped around the reel 22 rotatably mounted in a bracket 54 on the bow by a pin 56 and actuated by a handle or crank 58. The loop assembly 52 on the extended end of the line 20 is freely attached to the shafts 12 and 14, and with the arrow in the cocked position the loop assembly 52 is adjacent the head or point, as shown in FIG. 1, whereas as soon as the arrow is released the loop assembly slides to the opposite end or rear of the arrow, as shown in FIGURE 4.

It will be seen that the double shafts 12 and 14 together

with the space therebetween provide a trackway or trackway means and that the loop assembly 52 of the retrieving line provides a track follower. The space between the shafts 12 and 14 is open from a point at the forward end of the arrow preferably immediately behind the head thereof rearwardly entirely to the weld 26. The weld 26 will be seen to provide a limit or limit means on a rearward portion of the arrow for limiting movement of the track follower 52, whereby the arrow can be shot at a time when the follower or loop assembly 52 is in a portion of the trackway defined by shafts 12 and 14 and by the space therebetween, which portion is disposed far forwardly of the limit means or weld 26.

The modification of FIGURE 5 has its sides 100 and 102 exactly straight. The modification of FIGURE 7 has its sides 104 and 106 composed of two portions: major portions 110 and 112 forming substantially the entire length of the arrow rearwardly to a limit means or connection 120 of the arrow disposed at the rearward end thereof and interconnecting the shafts 12" and 14"; and sides 104 and 106 further having rearward end portions 130 and 132 defining a bow string notch 134 therebetween, with the side portions 110 and 130 separated by a recess 160 and with the side portions 112 and 132 separated by a recess 162.

The modification of FIGURE 5 also has a bow string notch 170 disposed between shafts or shaft portions 12' and 14' rearwardly of the limit means or weld 26.

It will be seen that if the arrow of FIGURE 3 were turned so that its substantially planar point or head 18 was disposed horizontally, then during shooting, the outer projecting portion 64 or 66 of the arrow would strike either that portion of the operator's hand which is being used as an arrow rest or would strike an arrow rest if the bow is of a type having an arrow rest, in either case causing an undesirable deflection of the arrow during arrow release. For that reason, the arrows of FIGURES 5 and 7 can be further defined as having top and bottom sides 180 and 182, respectively, for the arrow of FIGURE 5, and 190 and 192, respectively, for the arrow of FIGURE 7, which top and bottom sides are definable similarly to the sides 100, 102, 104, and 106, respectively, as regards the above described shape for preventing diversion.

It will be seen that at least one side of the arrow must have those of its outer surfaces which project the farthest to the one side of an arrow not projecting to such side of the arrow enough for causing substantial deflection of the arrow, whereby when such one side of the arrow is disposed against the side of a bow, the arrow will not be substantially deflected off the course by any portion of the arrow which might otherwise protrude sufficiently beyond said one side to cause substantial deflection of the arrow by striking the bow during arrow release.

It will be seen that the arrow modification of FIGURE 3 will not shoot in all positions with as great an accuracy as the modifications of FIGURES 5 and 7 because in FIGURE 3 the rearwardmost ends 64 and 66 of the arrow diverge outwardly whereby the projecting ends 64 or 66 will tend to engage the side of a bow during shooting causing the arrow to be deflected off course by striking the bow during arrow release.

From the foregoing description, it is thought to be obvious that an arrow assembly constructed in accordance with my invention is particularly well adapted for use, by reason of the convenience and facility with which it

may be assembled and operated, and it will also be obvious that my invention can be changed and modified without departing from the principles and spirit thereof, and for this reason, I do not wish to be understood as limiting myself to the precise arrangement and formation of the several parts herein shown in carrying out my invention in practice, except as claimed.

I claim:

1. An arrow providing longitudinal trackway means thereon, said trackway means being adapted to receive a track follower engaged with said trackway and attached to said arrow for the movement of said track follower only longitudinally of said arrow, limit means on the rearward portion of said arrow for limiting movement of said follower rearwardly with respect to said arrow, said trackway means extending from a portion of the arrow far enough forwardly from said limit means as to be disposed on the forward side of a bow handle at times when the arrow is in a drawn position immediately before release, whereby said arrow can be shot at a time when said follower is in a portion of said trackway forwardly of said limit means and will travel rearwardly to said limit means upon release of said arrow, said arrow having a bow string receiving notch in its rearward end, the majority of the length of said arrow being formed of multiple shafts at least two of which are spaced apart for defining the said trackway means, the said limit means being defined by a connection between said two shafts at the rearward end of the arrow, means interconnecting the forward ends of said shafts, means attached to the forward end of said arrow and defining a point, at least one side of said arrow having those of its outer surfaces which project the farthest to the said one side of said arrow not projecting to said one side of said arrow enough for causing substantial deflection of said arrow whereby when said one side of said arrow is disposed against the side of a bow said arrow will not be substantially deflected off course by any portion of the arrow which might otherwise protrude sufficiently beyond said one side to cause substantial deflection of the arrow by striking the bow during arrow release.

2. The combination of claim 1 in which said arrow is formed of metal for providing strength with a minimum of cross-sectional area to encounter minimum water resistance for maximum water depth penetration.
